GARMENT HANGER

Albert Zifferblatt, 320 Ridgeview Drive, Palm Beach, Fla.

Filed Dec. 30, 1959, Ser. No. 58,860

Term of patent 14 years

(Cl. D80—8)

Fig. 1

Fig. 2

Fig. 3

I claim:

The ornamental design for a garment hanger, as shown and described.
